(57) CLAIM

The ornamental design of a plumber's body support pad, as
shown and described.

DESCRIPTION

FIG. 1 is a perspective view of a plumber's body support pad
of my new design;

FIG. 2 is a top plan view thereof;

FIG. 3 is a front elevational view thereof;

FIG. 4 is a rear elevational view thereof;

FIG. 5 is a side elevational view thereof, the opposite side
being a mirror image of FIG. 5; and,

FIG. 6 is a bottom plan view thereof.
